UNITED STATES PATENT OFFICE.

JOHN REID, OF NEW YORK, N. Y.

SHIP.

1,271,081.

Specification of Letters Patent. Patented July 2, 1918.

Application filed February 19, 1916, Serial No. 79,396. Renewed June 4, 1917. Serial No. 172,797.

To all whom it may concern:

Be it known that I, JOHN REID, a subject of the King of Great Britain, and resident of 17 Battery Place, city of New York, 5 State of New York, United States of America, have invented certain new and useful Improvements in Ships, of which the following is the specification.

The invention relates to improvements in 10 ships as described in the present specification and shown in the diagrammatic drawings herewith.

The invention consists essentially in the 15 novel arrangement of the motive power machines and their controlling and supply apparatus, whereby not more than one of the power units is liable at any one time to be disturbed by external disasters to the ship and that infrequently.

20 The objects of the invention are to put the complete control of the ship in the hands of a competent officer, who shall have it within his own power to regulate her movements, to guard against the danger 25 of injury from external sources, that will disable the ship by reason of the dislocation of a vital part affecting all the machinery as is possible under known mechanisms, to distribute the controlling apparatus so that 30 it will be available under almost any conditions, to so bury the vital parts to the motive power within the bowels of the ship as to make them unaccessible except by tortuous passages even from the interior of the 35 vessel and generally to provide a ship structure that aids in avoiding or minimizing the consequences of such disasters as occurred in the wrecking of the steamships Titanic, Lusitania, Persia and many others.

40 In the drawings, Figure 1 is a diagrammatic view, showing a plan of the arrangement of the motive power parts.

Fig. 2 is a diagrammatic view showing 45 a plan in cross section.

Fig. 3 is plan showing diagrammatically a general view of the wiring.

Like numerals of reference indicate corresponding parts in each figure.

It is important to notice that in all high 50 powered ships up to the present time it has been found necessary, for simplicity and convenience to group the propelling engines in a single large compartment occupying as a rule one of the largest and most important sections of the vessel's length, such

compartment being possibly subdivided, in twin screw or quadruple screw ships, by longitudinal bulkheads provided with watertight doors for the convenience of the engineer, officers and crew. When it is considered that the propelling engines, even when gearing is introduced, must be located on the ends of the driving shafts and must all be controlled from one station, the necessity for such an arrangement, which, as 60 already pointed out, is full of danger in the event of damage occurring to the vessel from destructive outside forces, is at once apparent. It is the object of the present invention to avoid such concentration of the 65 propelling machinery and the dangerously large compartments which such an arrangement entails.

Referring to the drawings, 1, 2, 3 and 4 are the central longitudinal engine rooms 75 with sealed longitudinal bulkheads 5 and at each end crossed by the transverse bulkheads 6, in all of which it is proposed to have no water tight or other doors or causes of weakness.

The electrical power generating units 7, 80 8, and 9, 10 and 11, and 12 and 13 are situated in the said engine rooms respectively.

The boilers 14, 15 and 16, 17 and 18, and 85 19 and 20 are contained in sealed chambers between the longitudinal bulkheads 5 and the inner skin 21 and are divided transversely by the extensions 22 of the transverse bulkheads 6.

It will thus be seen that there are three 90 large generating stations separated from each other by transverse bulkheads and one smaller generating station just forward of the propelling motor chambers 23, 24 and 25, in which are contained the electric motors 26 and 27, 28 and 29, and 30 and 31 respectively, said motors operating their respective large gear wheels 32, 33 and 34 in the chambers 35, 36 and 37.

The control station 38 through which all 100 the cables from the generators pass is situated about midships at the motor divisions and other controllers are suitably connected on the bridge and at various parts of the vessel, as for instance on a warship where 105 gun turrets and various war mechanism may be operated by the generated power.

A system of signals or telegraph must of course be arranged from the control to the boiler rooms, so that the fire crew may be 110

guided in making and reducing steam according to the number of generators in operation.

The said generating units in the central engine rooms are based upon the surface condensers 39, and above the said engine rooms is a communicating passage or tunnel 40 in which all power cables will be carried from place to place and through 10 which access will also be arranged to the various boiler and engine rooms.

The openings 46 in the form of covered manholes are made in the roof of the engine rooms within the airlock divisions of 15 the passage 40, thereby affording access to said engine rooms.

The passage 40 is directly under the watertight deck 41, but as arranged presents no element of danger because access to this 20 passage will be through the airlocks 42 and the vessel will have to sink or list on either side, so that water is well over the watertight deck 41, before any trouble results in using this passage.

25 Between the inner and outer skins adjoining the boiler rooms are the oil fuel compartments 43 and between the inner and outer bottoms the reserve oil fuel compartments 44. It will be seen that the machinery and fuel are contained within a comparatively small compass and free from any ordinary accident or attack.

The steam equipment may be replaced by 30 internal combustion engines and the arrangement of the rooms and their number changed to suit the circumstances under which the invention is used, and various changes may be made in carrying out the invention, so long as said changes are within 35 the scope of the claims for novelty following this description.

What I claim is:—

1. In a ship, a hull, a plurality of motive

machinery rooms, a chamber above said rooms forming a closed longitudinal passage, airlocks guarding the entrances to said passage, the walls and flooring of said rooms offering no means of ingress and egress to or from said rooms and the flooring of said airlocks having openings leading to said 50 rooms, and motive machinery in said rooms.

2. In a ship, a hull having a plurality of motive machinery rooms formed by longitudinal and transverse bulkheads and flooring, having no ingress openings and roofing 55 having ingress openings, an upper communicating chamber forming a central passage, airlocks communicating with the machinery rooms and the central passage by way of the roof and a watertight deck covering said 60 rooms.

3. A ship having a plurality of contiguous rooms with watertight walls, and provided with a watertight passage, airlocks 65 communicating with said passage and with a plurality of said compartments and a watertight deck over the passage and compartments.

4. In a ship, a hull, a plurality of bulkheads, longitudinal and lateral and dividing 70 the interior of the hull into chambers, certain of said chambers being allotted to the motive machinery and affording no access, except through the opening in the roof, other chambers being allotted to fuel, a 75 walled-in passage provided with air locks, the latter also in communication with the roof openings, cables carried in said passage, and control stations connected with said cables.

Signed at New York city this tenth day of February, 1916.

JOHN REID.
